[57] CLAIM

The ornamental design for a battery terminal connector, as shown and described.

DESCRIPTION

FIG. 1 is a perspective view of the battery terminal connector showing my new design;

FIG. 2 is a top plan view of the connector shown in FIG. 1;

FIG. 3 is a left end elevational view of the connector shown in FIG. 2;

FIG. 4 is a right end elevational view of the connector shown in FIG. 2;

FIG. 5 is a front elevational view of the connector shown in FIG. 2;

FIG. 6 is a rear elevational view of the connector shown in FIG. 2; and

FIG. 7 is a bottom plan view of the connector shown in FIG. 2 but with the connector rotated 180°.
